UNITED STATES PATENT OFFICE

2,071,160

FLOOR DRAIN

Edward W. N. Boosey, Detroit, Mich.

Application June 22, 1934, Serial No. 731,919

7 Claims. (Cl. 210—56)

This invention relates to floor drains, the principal object being to provide a floor drain of such character of construction that the normal liquid level within the drain body is above the discharge outlet. The floor drain is adapted for use, for instance in garages or the like, where oil will be discharged into the drain, and the object is to provide a floor drain of a character to cause separation of the oil and water flowing thereto and permit the water to discharge to the sewer while the oil may be removed by hand or by means of a discharge outlet for oil at a level above the outlet for the water.

It is also a feature and object of this invention to provide a construction permitting accessibility to all parts of the drain through the grated inlet, a receptacle being removably supported within the drain body in which heavier waste materials may accumulate and thus providing a separation not only of the oil and water but also to separate therefrom the heavier greases and like waste material. By this arrangement the liquid oils are to a material degree cleaned of solid and semi-solid matter and such reclaimed oil may again be utilized in various ways and material flowing to the sewer is practically free from oil thus conforming to the requirement in our cities that no oil shall be discharged into sewers.

It is also an object of the invention to provide a construction that is comparatively simple and inexpensive in construction and of such character that when once installed can be readily maintained in its operative condition all as is herein-after more fully described.

These objects and the various novel features of the invention are hereinafter more fully described and claimed, and the preferred form of construction of a floor drain embodying my invention is shown in the accompanying drawing in

40 which—

Fig. 1 is a vertical section of my improved floor drain taken on line 1—1 of Fig. 2.

Fig. 2 is a cross section thereof taken on line 2—2 of Fig. 1.

45 The drain consists of a body preferably formed of two sections 1 and 2, the lower section having a hub 3 to receive the open lower end 4 of the section 1. Bolts 5 may be provided to secure the two sections together and a caulking 6 is provided in the space between the hub 3 and the lower end of the section 1 as will be understood from Fig. 1. The section 2 has a closed bottom 7 and the upper section 1 has a hub portion 8 at its inlet end practically flush with the floor line 55 which, as shown at 9, is at a slight angle to the

horizontal to cause material to flow readily to the drain. Just below the hub 8 is provided a ledge or shoulder 11 on which is loosely positioned a drain plate 12 having a central aperture here shown as a threaded aperture to receive a separate tubular discharge sleeve or conduit 13. The drain plate has apertures 14 on opposite sides of the threaded aperture for the tube 13 and a U-shaped handle member 15 is provided with its opposite parallel leg portions extending through 10 the apertures 14 and provided with a nut on the lower end.

The handle is preferably loosely positioned and when the grating 10 is removed this handle is in position to be grasped by the operator and this drain plate lifted from position to provide access to the interior of the drain body. The upper section of the drain body has a transverse wall 16 and a sloping wall 17 extends from the upper end of the wall 16 to the flange or ledge 11. These walls 16 and 11 form a separate chamber in the upper section of the drain body and this chamber is again divided by a wall 18 terminating below the sloping wall 17 thereby providing a chamber 19 on one side of the wall 18 and 20 on the other as will be understood from Fig. 2. This chamber has a bottom wall 21 and thus is closed to the interior of the drain with the exception that the bottom wall 21 under the chamber 19 has a threaded aperture to receive a tube 22 which extends very nearly to the bottom of the lower section 2. The tube is open-ended as shown. The side wall of the upper section 1 has a threaded aperture to receive a hub 23 which in turn receives the end of the sewer pipe (not shown). 30 The wall 18 between the chambers 19 and 20 has a vertical slot 24, the bottom of which is above the lower edge of the outlet in which the hub 23 is inserted, the purpose of which slot is herein-after described. The upper section 1 also has a 40 number of lugs 25 on the wall 16 and on the outer wall of a section 1 as will be understood from Fig. 2, and a catch basin 26 is provided with a rim 27 which lies on the said lugs. The flange 27 is spaced from the wall 16 and the section 1 providing an opening 28 thereabout through which liquid overflowing from the receptacle 26 may pass into the main body 1 and 2 of the drain.

In some cases of installation, it is desirable to have an oil outlet and this is here shown as a 50 pipe 29 threaded in a hub 30 provided in the section 1, the bottom of which is located above the water level and preferably above the bottom of the slot 24 on the opposite side of the drain body.

The oil outlet 29 may be dispensed with in some installations where it is not practicable to provide a receiving basin to which it discharges and in such case the oil must of necessity be removed from the drain by hand and this is readily accomplished due to the fact that the drain plate as well as the receptacle 26 are loosely mounted and readily removable through the upper end of the section 1.

10 This invention seeks to provide a construction in which the water may flow out of the drain head due to the outlet being at a lower level than the oil outlet and thus retain a body of oil on the surface of the water above the level of the water outlet and the construction shown accomplishes this purpose as will be understood from the following description of the operation of the device.

Preparatory to use of the device, the drain is 20 filled with water to the water level indicated by dotted lines *a*. Thereafter as water, oil, grease and dirt from the floor of a garage, for instance, flows into the drain it passes from the drain plate through the tube 13 into the receptacle 25 26 where the heavier material tends to remain and the lighter materials flow upward out of the receptacle and downward through the space 28 into the body of water.

The oil will float on the surface of the water 30 and, as the water level through introduction of the above mentioned material is raised, water flows out of the outlet and into the sewer line connected with the hub 23. The oil floating on the top of the water can pass out through the outlet 29 and thus be separated both from the heavier greases and material caught in the receptacle 26 and water and discharged to a storage tank and may eventually be reclaimed or purified by separation of the oil into its lighter and heavier constituents. The water, it will be noted, passes upwardly through the tube 22 into the chamber 19 and if there is a slow accumulation of water it will pass the slot 24 into the chamber 20 and thence out through the hub 23 and sewer 40 line connected therewith. If there is a rapid accumulation of water, as is oftentimes the case, the water level will raise to the top of the dividing wall 18 and flow over this wall into the chamber 20 and thence to the outlet. Thus, in 45 what may be termed normal use, where small quantities of water and oil are discharged into the drain, the water level is at the dotted line *a* but when a larger quantity is discharged into the receptacle the water is at the same level as the upper edge of the wall 18 and the water level 50 in either case is below the outlet 29 for the oil.

The main chamber, as previously stated, is closed at the top by the plate 12. The chamber is vented at the top just beneath this plate for 55 which purpose the side wall thereof is provided with a hub 50 for connection with a vent stack. The vent opening, it will be noted, is above the maximum level of the water within the body of the drain.

60 Thus, in the construction shown, there is no possibility of water flowing through the oil outlet 29 as the arrangement of the parts provides a well for the oil and water in which the oil has opportunity to rise to the surface of the water 65 and this is due to the provision of the wall 16 having the two chambers therein and the tube 22 extending to the bottom of the drain body and through which only the water will pass. This 70 general arrangement of parts constitutes one of 75 the principal features of my invention, namely,

the construction of a floor drain in which the oil outlet is above the main outlet of the drain body and in which the water level also is above the main outlet from the drain and by this arrangement I am able to provide for an automatic separation of the oil and water, dirt and grease, the latter of which accumulates in the receptacle 26 thereby preventing such grease and dirt from passing into the sewer to accumulate therein and discharging the oil comparatively free of dirt and grease and such heavier materials as will separate naturally by gravity in the receptacle 26.

It is also pointed out that the outlet 29 may be dispensed with for the reason that the oil floating on the surface of the water will accumulate 15 in the main portion of the body section 1 until it stands at a level slightly above the grate 10 which should be notice to the attendant that the drain should be emptied of oil. Oil will accumulate as stated with the main outlet of the 20 drain in the neighborhood of ten inches below the grate 10. Under this condition oil will be readily observable at the grate particularly when considerable water and material are flushed into the device in which case the water level will be 25 raised to the top of the wall 18 and will gradually normally fall to the level indicated by the dotted line *a* due to seepage of the water through the slot 24.

It is believed from the foregoing description 30 that the principal object and feature of the invention, namely, the separation of oil from water and the heavier waste materials such as grease and dirt and the like is accomplished and that no oil will flow into the sewer through the outlet 35 from the drain and that the device may be readily cleaned by removal of the grate, the drain plate 12, and receptacle 26 which provides access to the main body of the drain and as the wall 17 has an opening closed by the plug 49 of 40 which one is provided for the chamber 19 and one for the chamber 20, access is had to these chambers for cleaning purposes.

By the arrangement of the parts described, the minimum water level within the drain body 45 is maintained above the lowermost point of the outlet to which the hub 23 is connected and a maximum water level is prevented from being materially above the uppermost point of the said outlet. This is secured by the provision of the 50 wall 18 having the slot 24 therein, the lower edge of which slot is above the lowermost point of the outlet and the upper edge of the wall over which the water must flow from the section 19 of the outlet chamber to the section 20 thereof is preferably slightly above the uppermost point of the outlet. As the oil outlet 29 has its lowermost point preferably above the possible maximum water level no water may flow out of the said oil outlet and by the provision of the outlet chamber consisting of the two sections 19 and 20 and the tubular member 22 opening to adjacent the bottom of the drain body no oil can pass to the outlet chamber. Thus by the construction described including the receptacle 26, I am able to 65 separately dispose of the oil, the water and the dirt, grease, etc., passing in mass into the drain body.

It is also to be observed that various alterations 70 in form and arrangement of parts of the structure may be made and still secure applicant's principal object of maintenance of an oil level above the outlet to the drain and other features without departing from the spirit and scope of the invention as defined by the appended claims. 75

Having thus briefly described my invention, its utility and mode of operation, what I claim and desire to secure by Letters Patent of the United States is—

5. 1. A floor drain for the purpose described comprising a drain body having an inlet at its upper end, means within the drain body separating the same into a main chamber and an outlet chamber, a water outlet opening to the said outlet chamber, an oil outlet opening to the main chamber, the lowermost point of which is above the uppermost point of the water outlet, and means 10 in the outlet chamber providing for a minimum water level above the lowermost point of the water outlet and a maximum water level at about the uppermost point of the outlet.
2. A floor drain comprising a drain body having an inlet at the upper end and an outlet on one side thereof below the upper end, said body 20 being separated into a main chamber into which material from the inlet directly flows and an outlet chamber opening to the main chamber adjacent the bottom thereof, a wall in the said outlet chamber, the upper edge of which is above the uppermost point of the outlet, the parts being so arranged that water flowing upwardly to the outlet chamber is required to flow over the said wall to the said outlet, and an oil outlet on one side of the body, the lowermost point of which 30 is above the upper edge of the said wall of the outlet chamber.
3. A floor drain for the purpose described comprising a drain body having an inlet at its upper end, a receptacle within the body into which material flowing into the drain passes and from which the material passes by overflowing the upper end of the receptacle and into the body, said receptacle providing a means for deposition of waste material such as grease, dirt and the like, said drain body having an outlet for water on one side thereof and an oil outlet at a level above the said water outlet, means for maintaining the water level in the drain body at a point above the lowermost point of the water outlet 45 and below the lowermost point of the oil outlet whereby oil may be discharged from the interior of the chamber separately from the water.
4. A floor drain comprising a drain body having an inlet at its upper end, an outlet on one side therebelow, means within the body separating the same into a main chamber and an outlet chamber to which the aforesaid outlet opens, said outlet chamber opening to the main chamber adjacent the bottom thereof whereby liquid 55 may pass upwardly from the bottom of the main chamber to the outlet chamber, a wall in the outlet chamber dividing the same into two parts to one of which the outlet opens and to the other of which fluid is discharged through the said opening to the main chamber, the upper end of said wall being above the uppermost point of the outlet whereby water on flowing upwardly to the chamber on the opposite side of the said wall will flow into the portion of the chamber open to the outlet when the water has attained the level of the upper end of the said wall, and an oil outlet open to the main body, the lowermost point of which is above the maximum level determined by the upper edge of the said wall.
- 70 5. A floor drain comprising a drain body hav-
- ing an inlet at its upper end, a water outlet on one side thereof below the upper end, an outlet chamber provided in the main body having an opening adjacent the bottom of the body through which fluid may flow to the outlet chamber, said outlet chamber being formed of two sections into one of which water flows from the drain body and the other of which is freely open to the outlet, the wall between the two sections of the outlet chamber having a slot, the lowermost point of which is above the lowermost point of the water outlet and the upper edge of which wall is approximately at the uppermost point of the water outlet, an oil inlet opening to the drain body, the lowermost point of which is 15 above the upper edge of the said wall between the two sections of the outlet chamber, a drain plate at the inlet end of the body having a depending tubular portion through which all material must pass from the inlet, a receptacle 20 movably supported in the body into which the said depending tubular portion extends and providing a structure in which material flowing thereto must pass into the main body above the lower end of the said depending tubular portion 25 whereby waste material of greater specific gravity than oil and water tends to accumulate by gravity, the arrangement of the water outlet, outlet chamber, and oil outlet providing a means whereby oil only may be discharged through the 30 outlet and water only through the water outlet.
6. A floor drain comprising a drain body separated into a main chamber and an outlet chamber, said body having an inlet at its upper end 35 and an outlet therebelow in the side of the drain body, a dividing wall in said outlet chamber separating the same into sections to one of which the outlet is open and the other of which is open through its bottom to the lower end of the main chamber, said dividing wall having its upper edge at approximately the same level as the uppermost point of the outlet, said dividing wall further having a vertical slot providing a passage-way for water between the two chambers, the 40 lowermost point of which is above the lowermost point of the outlet, said outlet chamber and slotted wall providing means determining the minimum and maximum water levels within the body of the drain, the arrangement being such 45 that on slow accumulation of water, oil etc., in the drain body the water is discharged to the said outlet chamber and passes through the slot to the outlet and upon a sufficient amount of water being discharged into the drain body the 50 water rises and flows over the upper edges of the said wall to the outlet, said outlet chamber being closed to the main chamber except through the said opening in communication with the bottom thereof.
7. A floor drain comprising a drain body having an inlet at its upper end to receive oil and water, an oil outlet on one side thereof, a water outlet, means associated with the water outlet for maintaining a minimum water level in the 55 drain body above the lowermost point of the water outlet, and a maximum water level below the lowermost point of the oil outlet.

EDWARD W. N. BOOSEY.
